Delaware

Application November 1, 1943, Serial No. 508,572

3 Claims. (Cl. 261—34)

1

This invention relates to charge forming devices for internal combustion engines and consists particularly in means for supplying an additional fuel charge to the engine under certain conditions together with means to incapacitate the same under other conditions.

Where an automotive engine carburetor is provided with a throttle operated accelerating pump, it is frequently undesirable to have the pump discharge into the mixture conduit when the suction therein exceeds a certain value, irrespective of throttle movements. There have been devices for preventing the pump discharge under certain conditions, but so far as present inventors are aware, there has been no device which is effectively responsive to engine suction alone to prevent the pump discharge.

Accordingly, the object of the present invention is to provide a carburetor accelerating pump structure including means for definitely preventing the pump discharge under high suction conditions, irrespective of throttle movements.

This object and other more detailed objects hereafter appearing are attained substantially by the structure illustrated in the accompanying drawing, in which

Fig. 1 is a vertical section through a carburetor, somewhat diagrammatically arranged, and illustrating one form of the invention.

Fig. 2 is a similar view of a carburetor embodying a modification.

Fig. 3 is a detail view showing another modification.

In each of the forms shown, the carburetor comprises a downdraft mixture barrel including an air inlet portion 5, mixing chamber 6, a series of venturis 7, an outlet portion 8, flanged as at 9 for attachment to the usual engine intake manifold (not shown). A butterfly-type throttle valve 10 controls the discharge of combustible mixture from the carburetor. Adjacent the barrel there is provided a bowl 11 in which fuel is maintained at a substantially constant level by float 12 and needle valve mechanism (not shown).

The main fuel supply passes through a metering orifice element 14 and upwardly inclined main fuel passage 15 communicating by means of nozzle 16 with the smallest venturi 7. Fuel for idling is supplied through passage 17, extending upwardly from inclined passage 15, and a downwardly extending passage 18 terminating in idling port 19 adjacent the edge of the throttle plate when closed. Metering orifice 14 is controlled by a metering pin 20 operated from the throttle by 50

a centrally pivoted lever 21 and a link 22 connected to arm 23 rigid with the throttle shaft.

An accelerating pump is also provided in the bowl including cylinder 25 and piston 26 operated from the throttle by a split lever 27 and link 28 connected to arm 29 rigid with the throttle shaft. The parts of split lever 27 are yieldingly maintained in alignment by a coiled spring 30 so that the pressure which can be exerted upon piston 26 is limited by the strength of this spring.

Upon closing movement of the throttle, fuel is drawn into cylinder 25 through a passage 32 past inlet check 33. Upon opening movements of the throttle, fuel is forced by the piston into the mixture conduit.

In Fig. 1, the pump is discharged through outlet passage 34 and against a non-cylindrical needle element 35 resting in the upper part of outlet passage 34. An enlarged chamber 36 connects passage 34 with a downward passage 37 which opens into the mixture conduit posterior to throttle 10. A check ball 38 in chamber 36 normally seats against the upper edge of passage 37 and also rests against or just clears needle element 35. The arrangement of element 35 and ball check 38 is such that upon discharge of the pump, element 35 is raised by the pump pressure against the ball so as to tend to unseat the latter and permit the passage of pumped fuel into the mixture conduit. However, when the engine suction applied to the relatively large exposed face of ball 38 is above a predetermined degree, say 8" of mercury, the pump cannot produce sufficient pressure to lift the ball, because of yielding operation connection 27, 30 and, thereafter, the spring 30 is stretched and no fuel is pumped.

In Fig. 2, the pump discharge passage 40 is provided with a control valve 41 in the form of a goose neck stem which extends upwardly through a passage 42 intersecting discharge passage 40. Adjacent passage 42 is an enlarged chamber 43 in which there is slidably received a piston 44 constantly urged upwardly by a coiled compression spring 45, so as to normally urge valve 41 clear of its seat at the upper edge of pump discharge passage 46. Chamber 43 communicates with the mixture conduit posterior to the throttle by means of a suction passage 47. The arrangement is such that engine suction applied to the relatively large exposed surface of piston 44 tends to hold valve 41 against its seat, and when this suction exceeds a predetermined value, as in the first form, the maximum pump pressure, when applied to valve 41, is insufficient to unseat the same and the discharge of accelerating fuel is

3

prevented. This form shows pump discharge passage 42 connected to the pump cylinder above the piston by a by-pass 47 for return of pumped fuel to the pump cylinder when valve 41 is held closed. The by-pass, however, may be omitted where the pump operating mechanism is yieldable, as shown.

Any suitable type of accelerating pump may be used, preferably, provided with a yieldable pressure relief. Since an opening movement of the carburetor throttle is inevitably accompanied by a drop in suction in the mixture conduit posterior to the throttle, the pump may be operated by this suction as shown in Fig. 3. In this form, the pump piston 26a is rigidly connected to a suction piston 50, both being normally urged downwardly in cylinder 25a by a compression spring 51. A passage 52 connects suction chamber 53 to the mixture conduit posterior to the throttle. When a drop in intake suction occurs, spring 51 urges the piston downwardly to force fuel through outlet passage 34a, provided the control valve arrangement, as at 35, 38 in Fig. 1, permits. When the suction again increases, the pistons are lifted against spring 51. An air vent is shown at 52. Operation of the pump piston coincides with movements of the throttle, as in Figs. 1 and 2.

The structure may be modified in other respects as will occur to those skilled in the art. The exclusive use of all modifications as some within the scope of the appended claims is contemplated.

We claim:

1. In a charge forming device, a mixture conduit having a throttle therein, an accelerating pump, yieldable means to discharge said pump responsive to opening said throttle, a passageway between said accelerating pump discharge and said mixing conduit, a pair of oppositely facing valve seats formed in said passageway, a pressure actuated valve for one of said seats normally closing said passageway and unseated by fluid pressure from said pump, a suction responsive valve arranged for seating engagement with the opposite valve seat, said suction actuated valve being seated responsive to relatively high suction conditions in said mixture conduit for closing said passageway, and means for unseating said suction actuated valve upon operation of said pressure responsive valve.

2. In a charge forming device, a mixture conduit having a throttle therein, an accelerating pump, yieldable means to discharge said pump responsive to opening of said throttle, a passageway between said accelerating pump discharge and said mixing conduit, a pair of oppositely facing valve seats formed in said passageway, a pressure actuated valve for one of said seats normally closing said passageway and unseated by fluid pressure from said pump, a suction actuated valve arranged for seating engagement with the opposite valve seat, said suction actuated valve being seated responsive to relatively high suction conditions in said mixing conduit for closing said passageway and for applying pressure to said pressure actuated valve to assist in retaining said pressure actuated valve on its seat, and means for unseating said suction actuated valve under normal or low suction conditions upon operation of said pressure actuated valve.

3. In a charge forming device, a mixing conduit having a throttle therein, an accelerating pump, yielding means to discharge said pump responsive to opening of said throttle, intersecting passageways forming a connection between said pump discharge and said mixing conduit, a pair of oppositely facing valve seats formed in said intersecting passageways, one of said seats being located in the first of said passageways, the other seat being located at the intersection of said passageways, a pressure actuated valve for the first of said seats normally closing the first of said passageways and unseated by fluid pressure from said pump, a suction actuated valve arranged for seating with the opposite valve seat, said suction actuated valve being seated responsive to relatively high suction conditions in said mixing conduit for closing the second of said passageways and for applying pressure to said pressure actuated valve to assist in retaining said pressure actuated valve on its seat, and means for unseating said suction actuated valve under normal or low suction conditions upon operation of said pressure actuated valve.
